UNITED STATES PATENT OFFICE.

WILLIAM GRANGE, OF PHILADELPHIA, PENNSYLVANIA.

DESIGN FOR A CASING FOR CANS.

SPECIFICATION forming part of Design No. 17,221, dated March 29, 1887.

Application filed January 20, 1887. Serial No. 224,958. Term of patent 14 years.

To all whom it may concern:

Be it known that I, WILLIAM GRANGE, a citizen of the United States, residing at Philadelphia, in the county of Philadelphia and 5 State of Pennsylvania, have invented certain new and useful Improvements in Designs for Casings for Cans for Oil, &c.; and I do hereby declare the following to be a full, clear, and exact description of the invention, reference 10 being had to the accompanying drawing, which forms part of this specification, in which the figure is a side elevation illustrating my design.

My design for casing of a can consists in the 15 surface ornamentation of said casing.

A represents the can, and B the casing or body-covering. The surface of said body is mainly covered or formed with projections C, of pyramidal shape, or protuberances having 20 four tapering or inclining sides with rounded or blunt apices. These projections are in ranks or rows divided or separated by hori-

zontal and vertical grooves or channels. There is a vertical plain or flat portion, D, of the casing, having perforations resembling letters, 25 being one above the other.

What I claim as my design is—

1. The design for cans, consisting of the cylindrical casing having pyramidal projections with blunt apices of rectangular form, as shown 30 and described.

2. The design for a casing for cans, consisting of a surface mainly covered or provided with pyramidal projections or four-sided protuberances with rounded or blunt apices, said 35 surface having a plain vertical portion with perforations resembling letters through the same, substantially as shown and described.

In testimony that I claim the foregoing I have hereunto set my hand.

WILLIAM GRANGE.
